UNITED STATES PATENT OFFICE.

JAMES L. NIX, OF HOMER CITY, PENNSYLVANIA.

HEATING APPARATUS FOR INCUBATORS.

No. 877,586.

Specification of Letters Patent.

Patented Jan. 28, 1908.

Application filed November 23, 1905. Serial No. 288,766.

To all whom it may concern:

Be it known that I, JAMES L. NIX, a citizen of the United States, and resident of Homer City, Pennsylvania, have invented certain new and useful Improvements in Heating Apparatus for Incubators, of which the following is a specification.

My invention relates to improvements in heating apparatus for incubators, and has for its object to provide means for the equal distribution of heat throughout the egg-chamber of an incubator.

In the drawings—Figure 1 is a perspective view of an incubator embodying the principles of my invention, the incubator being cut away in vertical longitudinal mid-section. Fig. 2 is a perspective view of the heat-diffusing apparatus. Fig. 3 is a longitudinal vertical view in mid-section of the same.

My invention relates to that class of incubators in which the egg-chamber is heated by radiation from a hot air receptacle, and in which the receptacle is heated by the introduction of fumes from a lamp, or other suitable heat medium.

In the devices of this character, the fumes are introduced to the heating-receptacle, and find an outlet from the heating-receptacle to the exterior of the incubator, while between their introduction to the heating-receptacle and their exit from that receptacle, they serve to heat the metallic bottom of said receptacle, which in turn heats the air within the egg-chamber by radiation. The difficulty attendant upon this mode of heating has been found to reside mainly in the creation of eddying currents of air within the heating-receptacle. Where these currents occur, they cause unequal heat distribution, frequently to such an extent as to impair or destroy the usefulness of the incubator. To remedy this defect, I have devised the following apparatus. I provide a heating-receptacle, comprising a metallic bottom 5 and a top 6. This heat-receptacle may be rectangular in horizontal cross-section, as shown in Figs. 1, 2 and 3. The flue 7 passes vertically through the bottom 5 and top 6, the top 6 being provided with an opening 8 for that purpose. The flue 7 is provided with a horizontal flue 9, which extends into the heating-receptacle 10, and preferably extends to a point beyond the center of the said heating-receptacle 10. The flue 7 is adapted to receive at its lower extremity the

chimney of the lamp or some other source of heat supply, the fumes from which will, when the top opening 11 of the said flue 7 is closed, pass horizontally through the flue 9 and be discharged from the open end of said flue 9 into the heating-receptacle 10. Above the metallic bottom 5, I have provided a rigid sheet 12, whose ends are bent over, as indicated by the numeral 13, in order that the sheet 12 may be elevated a slight distance above the upper surface of the bottom 5, and be parallel therewith. Upon the upper side of the sheet 12, I have provided a housing 13^a inclosing the flue 9 in the manner shown in the drawings, and being open at its top. The sheet 12 is cut away at the bottom of the housing 13^a. The flue 9 is secured within the housing 13^a by means of one or more brackets 14. The heating receptacle 10 is also provided with a vertical flue 15 projecting through the top 6 to the exterior of the incubator, and its lower opening being near to the bottom of the heat-receptacle.

By the described apparatus, I have provided a heating-receptacle having what may be termed a double bottom, the air-space between the sheets 12 and 5 being exceedingly thin. The heat of the flue 9 causes the air surrounding the flue 9 and within the housing 13^a to be first heated. This air being heated, rises and draws after it a supply of colder air through the thin air-space between the sheets 12 and 5. In this manner, the air within the heating-receptacle 10 is in constant motion, and being compelled to circulate through the thin air-space referred to, the formation of eddying currents is prevented, and a substantially uniform distribution of heat throughout the entire surface of the bottom 5 is accomplished.

Having thus described my invention, what I claim as new and desire to have secured to me by the grant of Letters Patent, is:

1. In a device of the class described, a heating-receptacle having a metallic bottom, a metallic sheet mounted above and parallel with said bottom in such a manner as to leave a thin air-space between the same and said bottom, a heating-flue horizontally disposed upon said metallic sheet, and a housing disposed around said flue said housing being open at its top and bottom, said metallic sheet having an opening therein which registers with the open bottom of the housing substantially as described.

2. In an incubator, a heating-receptacle comprising a bottom and top, a horizontal flue, a housing having vertical walls surrounding said flue, said housing being open at its top and bottom, a metallic sheet whereon said housing is mounted said metallic sheet having an opening therein which registers with the open bottom of the housing, and a metallic receptacle bottom mounted beneath

and parallel with said sheet, substantially as 10 described.

In testimony whereof, I have signed my name to this specification, in presence of two subscribing witnesses.

JAMES L. NIX.
